[57] CLAIM

The ornamental design for an automobile steering wheel, as shown and described.

DESCRIPTION

FIG. 1 is a front elevation view of an automobile steering wheel showing our new design;

FIG. 2 is a perspective view thereof from the right of FIG. 1 but rotated 90° counterclockwise; and

FIG. 3 is a bottom rear perspective view thereof.

The side opposite that shown in FIG. 2 is a mirror image thereof.
